UNITED STATES PATENT OFFICE

REGINALD JAMES MILLER, OF LONDON, ENGLAND, ASSIGNOR, BY MESNE ASSIGNMENTS,
TO WESTERN ELECTRIC COMPANY, INCORPORATED, A CORPORATION OF NEW YORK

ELECTRICAL SOUND REPRODUCTION OF GRAMOPHONE AND LIKE RECORDS

Application filed January 23, 1928, Serial No. 248,953, and in Great Britain January 24, 1927.

This invention relates to the sound reproduction of gramophone and like records wherein electrical or electro-magnetic means associated with a source of potential are actuated directly by a stylus which is in contact with the record, and the invention has for its object to secure more faithful and better controlled reproduction of the recorded sounds than are obtained hitherto.

10 According to one embodiment the invention comprises an electrical sound reproducer provided with a variable inductive energy translator having a movable element which carries a plate of a condenser, means being provided for transmitting mechanical vibrations to said movable element.

According to another aspect the invention comprises an arrangement in which the mechanical vibrations of a stylus due to its contact with a gramophone or like record are converted into electrical oscillations through the medium of a condenser coupled mechanically to the moving coil of an electromagnetic reproducer whereby both are actuated simultaneously and directly by said stylus as it vibrates.

The condenser may comprise one or more stationary insulated conducting plates in proximity to which may be disposed one or 30 more movable insulated conducting plates to which a stylus adapted to contact with a gramophone or other record imparts movement; said movable plate or plates being connected positively to the moving coil of a known form of electromagnetic reproducer.

The invention will be more clearly understood by reference to the appended drawing in which Fig. 1 is an inverted plan view of the reproducer according to the invention. 40 Fig. 2 is a front elevation of the parts shown in Fig. 1; Fig. 3 is a rear elevation thereof partly in section; Fig. 4 is a side elevation thereof and Fig. 5 is a circuit arrangement in which the reproducer may be conveniently arranged to perform its desired functions.

The holder 1, forming part of the energy translator, is pivoted in a bracket 2 carried by a block 3 which is secured to a permanent magnet 4. The holder is preferably of extremely light material so that its inertia is

small and its response to the stylus very sensitive. Compressed fibre may be used, or better still an extremely light aluminium alloy such as duralumin may be employed for this purpose. The bracket 2 may be of any suitable metal and carries a pivot 5 upon which the moving member 1 is hinged. The energy translator comprising a coil 6 carried by the upper part of the member 1 has leads connected to terminals 7, which may be conveniently mounted in a plate 8 secured to the magnet 4. Between pole pieces 11 of the said magnet and secured to the block 3 is a soft iron core 9, about which is supported the moving coil 6. A set screw 10 may be used in the ordinary way adjustably to secure the stylus in position. An insulated plate 12 extending preferably over the whole of one side of the member 1 is attached thereto and constitutes one electrode of a condenser. The other electrode consists of an insulated plate 13 which is fixed to the pole piece 11 in the manner shown. Connecting leads 14 join the condenser plates 12 and 13 to terminals 15. Adjustment of the movable part with respect to the fixed parts may be effected by means of set screws 16. Springs 17 tend to retain the holder in a normal position against the effects of the received vibrations.

The device is supported in a suitable carrier (not shown) which enables the stylus to engage with a gramophone record or the like so that lateral vibrations may be imparted to the movable holder 1. These vibrations cause varying currents to be induced in the coil 6 and simultaneously vary the capacity of the condenser represented by plates 12 and 13.

Fig. 5 shows a circuit arrangement in which the reproducer may be satisfactorily used. A three electrode discharge tube 18 has its input terminals connected to terminals 19, to which leads are connected to terminals 15 of the reproducer. The condenser 20 and resistance 21 are connected as shown so that for varying potentials received at terminals 19 the tube may serve as an amplifier to produce amplified current in the transformer 22.

Space discharge current is derived from a high tension battery (not shown) connected

between 28 and E. The low tension filament heating current is supplied from the battery (not shown) at terminals 27. In order that the condenser 12, 13 of the reproducer may be effective its plates have impressed thereon a steady potential conveniently obtained as shown by coupling one of terminals 19 through resistances 31, 30 to the high tension battery at terminal 28, the other plate (12) of the condenser being earthed. The condenser 32 and resistance 31 are provided merely to prevent any line or battery noises from reaching the grid of tube 18.

To the output winding of transformer 22 the moving coil 6 is connected through terminals 23. An appropriate receiving instrument is connected to terminals 26 or when the apparatus is used in a public address system, a further amplifier would be coupled to terminals 26, the loud speaker unit being then connected to the output of this amplifier.

Shunt resistances 24 and 25 are supplied in the output circuit of transformer 22 and these have variable tappings by means of which the relative magnitudes of the currents received from the moving coil 6 and from the tube 18 may be regulated to give most satisfactory reproduction in the receiving circuit coupled to terminals 26.

The operation of the reproducer circuit will be clearly understood from the drawing. The condenser 12, 13 with its associated circuits is sensitive to low frequency signals but for the high frequencies is not so responsive.

High frequencies however are faithfully reproduced by the moving coil element whose efficiency as a reproducer falls off at the lower frequencies. The entire range of frequencies is therefore impressed on the circuit of tube 18 and by this means with the help of regulator resistances 24 and 25 the vibrations of the reproducer may be converted into electrical waves whose characteristics faithfully represent the impressions of the record. Furthermore by suitable regulation the reproducer may be made to compensate at the lower frequencies for the known deficiencies inherent in existing loud speakers.

The above description has been restricted to the particular device and circuit illustrated, but many modifications and alterations may be made without departing from the principle of the invention. For example, it is conceivable that the above arrangements may be used in conjunction with, or in part be substituted by, a resistance varied in accordance with mechanical vibrations. The induced current may be set up in a stationary coil with a vibratable core instead of using the moving coil as above described.

While the invention has been described with reference to specific embodiments it is to be understood that the scope of the invention is not to be restricted thereto but only as defined in the appended claims.

What is claimed is:

1. In an electrical phonograph reproducer a variable inductive energy translator, a movable element comprised in said translator, a condenser comprised partly by said movable element, and means for transmitting mechanical vibrations to said movable element.

2. In an electrical phonograph reproducer, a magnet structure, a variable inductive energy translator situated in the field thereof, a condenser comprising a plate carried by said translator and a stationary plate carried by said magnet structure, and means for transmitting mechanical vibrations to said translator.

3. In an electrical phonograph reproducer, a magnet structure, a variable inductive energy translator situated in the field thereof, a coil on said translator, a condenser comprising a plate carried by said translator and a plate carried by said structure, a stylus for transferring mechanical vibrations to said translator, and connecting conductors for transferring the translated mechanical vibrations to an electrical circuit.

4. In an electrical phonograph reproducer, a permanent magnet, a moving coil in the field of said magnet, a movable member supporting said coil, a condenser comprising a plate supported by said movable member and a stationary plate secured to said magnet, a stylus support, and a stylus for transferring mechanical vibrations from a record to said movable member.

5. In an electrical phonograph reproducer, a magnet structure, a variable inductive energy translator situated in the field thereof, a coil on said translator, a condenser comprising a plate carried by said translator and a plate carried by said structure, a stylus for transferring mechanical vibrations to said translator, and conductors connecting said condenser to the input circuit of a vacuum tube amplifier and other conductors connecting said inductive energy translator to an output circuit of said vacuum tube.

6. A system for reproducing sound including a vibration translating device and a vacuum tube amplifier, the device comprising a vibrating body, a variable condenser adapted to be varied by the body and coupled to the input circuit of the amplifier, and a coil adapted to receive variations corresponding to the vibrations of the body and coupled to the output circuit of the amplifier.

7. In a vibration translating system, a vibrating body, a receiving circuit, a variable condenser coupled to the circuit and adapted to be varied by the body, and a coil independently coupled to the circuit and being inductively related to the body.

8. In a vibration translating device, a vibrating body, a vacuum tube amplifier, two circuits connecting the amplifier and the body, means associated with the body and

one of the circuits for generating variations inductively, and other means associated with the body and the other circuit for generating variations capacitatively.

5 9. An electric phonograph reproducer comprising a variable inductive energy translator, a variable capacitative energy translator, a vibratable actuating member common to the translators, and a stylus for transferring 10 mechanical vibrations to the member.

10 10. An electrical phonograph reproducer comprising two energy translators for translating mechanical vibrations into electrical variations, one translator being more sensitive to the lower frequencies whilst the other is more sensitive to the higher frequencies of 15 the range to be translated, a vibratable actuating member common to the translators, and a stylus for transferring mechanical vibrations 20 to the member.

11. In a device of the class described, a vibratory element, means carried thereby for supporting a phonographic stylus, a capacity unit comprising a condenser plate fixedly supported in juxtaposition to the said vibratory element and a companion condenser plate supported in spaced relation thereto by the said vibratory element, and an electromagnetic unit comprising a coil and an armature supported by said vibratory element in 30 the field of the coil.

12. In a device of the class described, a vibratory element, means carried thereby for supporting a phonographic stylus, a capacity unit comprising a condenser plate fixedly supported in juxtaposition to said vibratory element and a companion condenser plate supported in spaced relation thereto by said vibratory element, and an electromagnetic 35 unit comprising a fixed magnet, a coil arranged between the pole pieces of the magnet, and an armature supported by said vibratory element in the field of the coil and between the pole pieces of the magnet.

40 43 REGINALD JAMES MILLER.
